UNITED STATES PATENT OFFICE.

HAROLD E. YARROW, OF GLASGOW, SCOTLAND.

CIRCULATION IN WATER-TUBE BOILERS.

1,350,200.

Specification of Letters Patent. Patented Aug. 17, 1920.

Application filed October 30, 1917. Serial No. 199,311.

To all whom it may concern:

Be it known that I, HAROLD EDGAR YARROW, a subject of the King of Great Britain, residing in Glasgow, Scotland, have invented certain new and useful Improvements Relating to the Circulation in Water-Tube Boilers, of which the following is a specification.

The invention relates to means for improving the circulation in water tube boilers.

The high rate of combustion now possible with oil fuel makes it advisable to increase the upward velocity of the water circulation in those tubes which are nearest to the source of heat.

The section of a water drum of this class of boiler is usually circular, or approximately circular, the nest of tubes which convey the downward convection currents being placed on the side away from the fire, while those conveying the upward currents are on the side nearest to the source of heat. As a result of experiments on a large scale made by the inventor, it is found that motion in a circular direction, more or less following the contour of the section of the drum, is imparted to the water as it flows from the cooler to the more heated tubes. This motion is utilized, according to the invention, to cause a more rapid circulation of those tubes of the nest conveying the upward currents which are the nearest to the source of heat. For this purpose, the lower ends of those tubes of the fire rows in which it is required to increase the velocity of circulation, are prolonged on one side as shown, or by means of ferrules taking the place of the tube ends cut at the required angle, so as to facilitate the entrance of the water.

Alternatively to, or in combination with, this formation of the tubes, baffle plates may be placed at suitable positions in the nest of the fire rows, so as to deflect the water into those tubes of the nest which are nearest to the source of heat.

In the accompanying drawings the figure is a transverse vertical section through a boiler and a portion of the furnace through the tube plate of a water drum provided

with means according to the invention for increasing the velocity of circulation in the tubes nearest to the fire.

A are the tubes nearest the source of heat G in which it is desired to increase the velocity, B are tubes farthest from the fire, in which the circulation is downward, C are tubes of the fire row which receive less heat than A and in which the circulation may be less rapid. The path of the water circulation in the drum is shown by the arrows. The lower ends of the tubes A are prolonged on the sides toward the tubes B to facilitate the entrance of the water.

As an alternative to, or in combination with, this formation of the tubes, a baffle plate E, riveted or bolted to the top plate F, is shown between the second and third rows of fire tubes. This plate may be placed between any of the rows of fire tubes as may be considered advisable.

Having thus described the nature of the said invention and the best means I know of carrying the same into practical effect, I claim:

1. Means for obtaining an improved circulation of water in a water tube boiler, comprising a water drum of approximately circular cross section, a source of heat, and a nest of tubes communicating with said water drum, the tubes relatively near the source of heat conveying upward currents of water and the tubes farther from the source of heat conveying downward currents of water, the lower ends of tubes nearest the source of heat terminating in oblique sections so that the part of each of said last named tubes which is turned away from the source of heat is lower than the part toward said source, substantially as described.

2. Means for obtaining an improved circulation of water in a water tube boiler, comprising a water drum of approximately circular cross section, a source of heat, a nest of tubes communicating with said water drum, the tubes relatively near the source of heat conveying upward currents of water and the tubes farther from the source of

heat conveying downward currents of water, the lower ends of tubes nearest the source of heat terminating in oblique sections so that the part of each of said last named tubes which is turned away from the source of heat is lower than the part toward said source, and a baffle plate secured to the top of said drum and placed between the tubes so as to deflect the water into the tubes

nearest the source of heat, substantially as 10 described.

In testimony whereof I have signed my name to this specification in the presence of two subscribing witnesses.

HAROLD E. YARROW.
